TIMER ESCAPEMENT

Charles E. Godley, Ferndale, Mich., assignor to
King-Seeley Corporation, Ann Arbor, Mich., a
corporation of Michigan

Application November 24, 1941, Serial No. 420,288

15 Claims. (Cl. 58—117)

1

The present invention relates to timing devices, and in particular is directed to the provision of an improved timer for producing an audible or other signal, or other operation, at the expiration of a selectively adjustable interval; and this application is a continuation in part of applicant's copending application, Serial No. 379,925, filed February 21, 1941.

The principal objects of the present invention are to provide a timer of the above generally indicated character, embodying an improved clock movement which is economical of manufacture and assembly, and which is positive and reliable in operation; to provide such a timer embodying an improved positive escapement, employing a pallet adapted in one rotative position to lock the escapement wheel and adapted in another rotative position to permit the escapement wheel to advance; to provide such a structure, wherein the pallet is withdrawn from locking position by means of an extension spring, which is readily adjustable to alter the timing of the escapement and wherein the pallet is urged into locking position by the advance of the escapement wheel; and to generally improve the construction and arrangement of timing devices of the type to which the present invention relates.

With the above as well as other objects in view, which appear in the following description and in the appended claims, preferred but illustrative embodiments of the invention are shown in the accompanying drawings throughout the several views of which corresponding reference characters are used to designate corresponding parts and in which:

Figure 1 is a view in front elevation of a timer embodying the invention;

Fig. 2 is a view in axial vertical section through the timer of Fig. 1;

Fig. 3 is a detail view, taken along the line 3—3 of Fig. 2;

Fig. 4 is a fragmentary sectional view, taken along the line 4—4 of Fig. 2;

Fig. 5 is a detail view, taken along the line 5—5 of Fig. 2;

Fig. 6 is a detail view in section, taken along the line 6—6 of Fig. 5;

Fig. 7 is a view in section taken along the line 7—7 of Fig. 5;

Fig. 8 is a view in section taken along the line 8—8 of Fig. 2;

Fig. 9 is a view corresponding generally to Fig. 8, but showing the hammer cocking mechanism in the off or released position;

Fig. 10 is a view taken along the line 10—10 of Fig. 9;

Fig. 11 is a fragmentary detail view, taken along the line 11—11 of Fig. 8;

Fig. 12 is a fragmentary detail view, taken along the line 12—12 of Fig. 9;

Fig. 13 is a fragmentary detail view, taken along the line 13—13 of Fig. 9;

Fig. 14 is a fragmentary detail view, taken along the line 14—14 of Fig. 9;

Fig. 15 is a fragmentary detail view, taken along the line 15—15 of Fig. 10;

Fig. 16 is a diagrammatic view of the improved escapement, based upon Fig. 5, but drawn on an enlarged scale;

Fig. 17 is a view corresponding to Fig. 16, but showing the elements of escapement in different relative positions;

Fig. 18 is a view corresponding generally to Fig. 5, but showing the adaptability of the present escapement to wheels of different numbers of teeth;

Fig. 19 is a view in front elevation of a modified dial construction;

Fig. 20 is a view in elevation of a modified construction of an escape wheel;

Fig. 21 is a view taken at right angles to Fig. 20;

Fig. 22 is a plan view of a fixture for assembling the hereinafter described clutch connection;

Fig. 23 is a view in vertical central section, taken along the line 23—23 of Fig. 22;

Figs. 24, 25 and 26 are comparative views of a modified escapement construction;

Fig. 27 is a view similar to Fig. 24, showing a further modification of the escapement mechanism;

Fig. 28 is a side elevation of the balance staff and escapement element employed in Fig. 27; and

Fig. 29 is a view illustrating the manner in which the escapement element of Figs. 27 and 28 is formed.

It will be appreciated from a complete understanding of the present invention that the improvements thereof may be embodied in timing mechanism of widely varying specific constructions, and intended for a relatively wide variety of different purposes. Also, in a generic sense, the character of the signal produced by the device may be of either audible, visual, or other character. In an illustrative but not in a limiting sense, the present improvements are herein disclosed in connection with a timing unit which operates to provide an audible signal.

Referring more particularly to Figs. 1 and 2 of the drawings, the present mechanism comprises generally a hammer mechanism designated as a whole as 30, which is directly connected to a main arbor 32, which, in turn, is adapted to be rotated in a starting direction from a normal or starting direction by means of a setting dial 34 and which is driven in the opposite or timing direction by a movement designated as a whole as 36. It will be appreciated that the movement 36, which has a clutch connection with the arbor 30, is effective, upon release of the dial 34, to drive the hammer mechanism in the return direction

at a substantially uniform rate, and that, consequently, the time interval for which the device is set is determined by the degree of angular movement through which the arbor 32 and the hammer mechanism 39 are moved in the setting direction by the dial 34. As is described in more detail hereinafter, the setting movement of the dial also serves to wind or load the main spring 38, associated with the movement 36, and the initial setting movement also acts to cock the hammer mechanism 39. The hammer mechanism has associated therewith means to trip the same at the conclusion of the return movement, which tripping action enables the hammer mechanism to effect an operation. As previously mentioned, the hammer may, in a generic sense, be caused to effect a wide variety of operations and consequently, throughout the present description and in the claims, except where a specific type of operation is particularly referred to, the term hammer mechanism is used in a generic sense, as referring to a suitable operator or like part. In the present instance, the hammer mechanism is arranged to ring a bell, and as illustrated, the hammer mechanism is of the multiple type, and produces a succession of bell notes.

Considering the above-mentioned elements in more detail, and referring particularly to Figs. 2, 5 and 7, the movement 36 comprises a main gear 40, which drives the arbor 32 at a rate determined by the escapement. The escapement comprises the escapement wheel 42, a pallet 44, a balance wheel 46, and an adjustable pallet spring 48.

More specifically, the main gear 40 is rotatably journaled on a portion 50 formed on the arbor 32, and a face plate 52 secured to the back of the main gear 40 abuts a shoulder 54 formed on the arbor, thereby preventing movement of the gear 40 to the right relative to the arbor 32. The other face of the main gear 40 is provided with a face plate 56, which is also seated on the portion 50 and directly and frictionally engaged by a clutch plate 58. The plate 58 is rigidly secured to and directly rotatable with the arbor 32.

A feature of the present invention resides in the method of and arrangement for securing the clutch plate 58 to the arbor 32 and for accurately predetermining the pressure which the plate 58 exerts against the main gear 40, thereby, of course, determining the torque which the clutch can sustain without slippage. As clearly appears in Figs. 2 and 23, the inner marginal edge 60 of the clutch plate 58 seats against a relatively short flat portion 62 on the arbor 32, and, preferably, the righthand face of the clutch plate 58, immediately adjacent the central opening therein, lies slightly spaced from a shoulder 64 on the arbor 32. In accordance with the present invention, the central opening in the clutch plate 58 is given a slightly rough or toothed marginal surface, and also, prior to assembly thereof with the arbor 32 and the gear 40, the central portion of the clutch plate 58 is pressed from the main body of the plate. In assembly, after the main gear 40 is applied to the arbor 32, the clutch plate 58 is simply pressed thereon, and, it being understood that the opening in the clutch plate 58 is of a diameter very slightly less than the diameter of the portion 62 of the arbor, the pressing on of the clutch plate 58 causes the central opening therein to solidly bind upon the portion 62 with a ratchet action, which positively prevents removal thereof. The pressing on movement of the plate 58 ultimately brings the main body portion thereof

into frictional engagement with the face plate 56. The clutch plate 58 is preferably slightly cupped, with the concave face thereof presented to the face plate 56, and is also preferably provided with a series of equiangularly spaced, radially extending notches 59, four being preferable. These notches extend inwardly from the periphery of the plate 58 and their length is preferably between 50% and 75% of the radius of the plate 58. The plate 58 is preferably formed of springlike material, and consequently, in the assembled position of the parts, a substantial proportion of the originally concave facial area of the plate 58 resiliently engages the face plate 56 with a frictional holding effect which progressively increases as the pressing on movement of the clutch plate 58 is continued.

It will be understood, as hereinafter described, that even in the normal or zero setting of the timer, the main spring 38 is loaded to a substantial extent, and this loading is, of course, increased each time the dial is rotated to set the timer for a predetermined timing interval. The holding effect of the clutch connection between the members 56 and 58 must, of course, be sufficient to reliably sustain the maximum loading of the spring 38 without introducing slippage. On the other hand, in order to facilitate a winding operation, and also to minimize the duty of the clutch elements, it is desirable to maintain the slippage value of the clutch at as low a value as is consistent with the just-mentioned duty. These considerations make it desirable to accurately gauge the frictional holding effect of the clutch elements, and in accordance with the present invention, this may be accomplished as an incident to the above-mentioned pressing on operation.

Referring particularly to Figs. 22 and 23, an illustrative fixture comprises a die 51, having a pocket 53 therein, in which the clutch plate 58 may be seated, the form of the pocket being such that only the radially central parts of the plate 58 are engaged thereby. With plate 58 thus preliminarily positioned within the pocket 53, the arbor 32, with the plates 52 and 56 and the gear 40, previously assembled thereon, may be projected downwardly through the opening in the die 51 towards the position of the parts shown in Fig. 23. The latter projecting movement brings the gear 40 into relatively non-rotative engagement with a spring loaded indicating member 55. Preferably and as illustrated, this relatively non-rotative connection is afforded by forming the inner peripheral face of the member 55 as an internal gear with which the gear 40 may mesh. The assembly 55 is provided at one side with a pointer 57, which is adapted to register with a relatively fixed scale 61, and is also provided with a diametrically opposite extension 63 to which one end of the loading spring 65 is secured. The other end of the spring 65 is anchored. It will be understood that any suitable means (not shown) may be employed to rotatively support the assembly 55 above the die 51, the principal requirement being that the toothed portion of the assembly 55 shall be of sufficient depth so that the gear 40 remains meshed therewith throughout the full range of the pressing on movement of the clutch plate 58.

With the parts thus preliminarily positioned, a compressive force may be applied between the upper end of the arbor 32 (Fig. 23) and the die 51, which forces portion 62 on the arbor 32 through the roughened central opening in the

plate 58. Concurrently with the application of this pressing force, a rotative force may be applied to the arbor 32, so as to cause the same to rotate in a clockwise direction, as viewed in Fig. 22. The initial pressing on movement of the plate 58 affords a non-rotative connection between the plate 58 and the arbor 32. Consequently, this rotation of the arbor 32 drives the clutch plate 58. As soon as the pressing on movement is continued far enough to bring the clutch plate 58 into engagement with the face plate 56, a rotative force is applied through the clutch to the gear 49. This force tends to rotate the assembly 55 in a clockwise direction, as viewed in Fig. 22, which latter rotation stresses the spring 65. It will be evident that the degree to which the spring 65 is stressed, and, consequently, the scale reading to which the pointer 57 is moved, depends upon the frictional holding effect between the plates 56 and 58, and that this holding effect is progressively increased as the pressing on movement is continued. The assembly operation is, of course, completed when the pressing on movement brings the pointer 57 to the desired scale reading.

The main gear 40 drives the escapement through a train of intermediate gears comprising the pinions 70 and 72 and the gears 74 and 76 which are carried by a staff 78, and further comprising the pinions 80 and 82 and the gear 84, which are carried by the staff 86. The staff 86 also carries the escape wheel 42. The staffs 78 and 86, and the staff 90 which carries the balance wheel 46 and the pallet 44, are supported by front and rear movement plates 92 and 94, which, in turn, are rigidly maintained in predetermined spaced relation to each other by the hereinafter described pillars 96. As illustrated, the staffs 78 and 86 are each provided with reduced end portions, which are freely rotatable within corresponding bearing openings provided therefor in the movement plates 92 and 94, it being understood that the staffs are permitted to have a very slight amount of longitudinal play so as to insure a free running condition thereof. The opposite ends of the staff 90 are pointed, one such pointed end being received in a corresponding tapered seat formed in a plug 98 which is conventionally pressed through the movement plate 92. The other tapered end of the staff 90 is received in a corresponding tapered seat formed in a plug 100, which, in the preferred practice of the invention, is relatively freely slideable within the opening 102 provided therefor in the movement plate 94. A leaf spring 104, one end whereof is riveted to the movement plate 94 as by a rivet 106, has its other end 108 bearing directly upon the back of the plug 100, and acts to continuously urge the same towards the plug 98, thereby maintaining a predetermined loading between the staff 90 and its bearing. A limit to such inward movement is afforded by the shoulder 110 on the plug 100, and a limit to outward movement of the plug 100 is afforded by a member 112, carried by the hereinafter described hammer mechanism. It will be understood that the staffs 78 and 86 may be provided with bearings which correspond to those described for the staff 90, it being appreciated, however, that the latter type bearings are of principal importance in connection with the staff 90, since this staff is driven in one direction by the escapement spring 48, and consequently is considerably more sensitive to changes in bearing pressures than are the other staffs which are driven entirely by the relatively heavy main

spring 38. It is found in practice that certain of the assembly operations, which occur after the main and intermediate gears and the escapement elements are assembled between the movement plates 90 and 92, tend to distort the plates, and any binding and locking of the staff 90 which might otherwise be caused by such deformation is entirely overcome by the just-described free running bearings for the staff mentioned.

- 10 It will be appreciated that in usual constructions, a substantial part of the ticking noise produced by the operation of the escapement is due to the play which normally must be allowed between the balance staff and its bearings, which play enables the balance staff to oscillate in an axial direction. Constructions heretofore used have employed, of course, an adjustable bearing arrangement. The setting of the adjustable bearing is, however, a rather critical operation and one that complicates the assembly operation. 15 Moreover, at least some play must be left in the bearing, as will be understood, to accommodate changes in temperature and the like. The present arrangement not only eliminates these assembly difficulties, but also entirely eliminates the necessity for any play in the balance staff bearings, since the spring 104 serves to continuously hold both ends of the staff seated in the corresponding bearings. The elimination of this play in the bearings materially reduces the intensity of the ticking noise, particularly when the present bearing arrangement is employed in connection with a flexible escape wheel of the type shown in Figs. 20 and 21 and described herein- 20 after.

25 The movement plates 92 and 94 are also provided with aligned bearing openings in which the arbor 32 is journalled, it being noted that axial play of the arbor 32 is limited by the engagement 30 of the shoulder 91 thereon with the movement plate 94 and by the engagement of the shoulder 93 thereon with the movement plate 92.

35 The pinion 70, which directly meshes with the main gear 40, and the companion gear 74 are rigid 40 with respect to each other and are press fitted upon the corresponding shaft 78. The immediately adjacent pinion 72 and its gear 76 in turn are rigid with each other and are freely journalled on the staff 78 between the just mentioned gear 74 and a sleeve 114, which, in turn, is press fitted upon the staff 78. Similarly, the pinion 80 and the gear 84 are rigid with respect to each other and are press fitted upon the staff 86. The pinion 82 and the escapement wheel 42, in turn, are rigid with each other, and are freely journalled on the staff 86 between the gear 84 and a sleeve 116, which is press fitted on the staff 86.

45 It will be noted that each of the staffs 78 and 86 carry two gear and pinion assemblies, which pyramiding or doubling up of the gear and pinion assemblies is advantageous for several reasons. First, this pyramiding obviously reduces the required number of staffs, and thus not only simplifies the unit as a whole but reduces the space requirements thereof. Further, and of perhaps even greater importance, this pyramiding enables the load reactions on the staffs to be balanced out in such a way as to avoid any heretofore encountered binding of the staffs as the gears and pinions wear in.

50 Considering now the escapement mechanism, and referring particularly to Figs. 5, 6, 7, 16 and 17, the previously mentioned balance wheel 46, the pallet 44, and a spring hook 120 are press fitted upon the staff 90 and so rotate as a unit

therewith. The pallet 44 is formed to define a tooth 122 and a locking shoulder 124. The locking shoulder 124 co-operates with each tooth of the escape wheel 42 to momentarily stop rotation of the latter when the parts occupy the relative positions shown in Fig. 16, and the tooth 122 of the pallet 44 is engaged by each successive tooth of the escape wheel 42, upon release of such tooth from the shoulder 124, so as to rotate the pallet 44 from the position shown in Fig. 17 back to the blocking position shown in Fig. 16. The pallet 44 is rotated from the blocking position of Fig. 16 in a clockwise direction sufficiently far to release the escape wheel tooth from the shoulder 124, by means of the extension spring 48, one end whereof is hooked to the spring hook 120, and the other end whereof is secured to a bracket 126. The other end of the bracket 126 rides in a guide slot 128 formed in the bracket support 130, which support is rigidly secured to the adjacent movement plate 92. The bracket 126 also receives a threaded adjusting screw 132, which may be rotated in one direction to extend the spring 48. Rotation of the screw 132 in the opposite direction enables compression spring 134 to force the bracket 126 to the right, thereby shortening the spring 48. The use of an extension type spring for co-operating with the pallet 44 is regarded as a feature of the present construction, since such extension spring can very readily be adjusted after all of the parts are assembled, so as to vary the tension of the spring 48 throughout a very considerable range.

The parts are shown in Figure 5 in the position to which the pallet 44 is moved by the passage therewith of a tooth of the escape wheel 42. When the pallet 44 occupies the just mentioned position, the pilot spring 48 occupies an over center position in which it urges the pallet 44 in a clockwise direction, as viewed in Figures 5, 16 and 17. As long, however, as the pallet occupies the just mentioned position, it blocks the tooth b of the escape wheel 42 and holds the latter against rotation. The spring 48 is effective to move the pallet 44 from the just mentioned position toward the position shown in Fig. 17, during the course of which movement the shoulder 124 thereof passes out of blocking relation to the tooth b of the escape wheel 42, enabling the latter to start in a clockwise direction under the influence of the main spring 38, which, as described below, acts directly against the arbor 32, which arbor is clutched to the escape wheel 42 through the previously mentioned main gear 40 and the intermediate gears. As soon as the escape wheel 42 is free of the shoulder 124, the tooth b thereof moves toward the tooth 122 of the pallet 44, which latter tooth is now in the path of movement of the tooth b. Consequently, the tooth b of the escape wheel 42 strikes the tooth 122 of the pallet 44 and rocks the latter from the position of Fig. 17 to the position of Fig. 16, during which movement the pallet spring 48 is again loaded. This movement of pallet 44 brings the shoulder 124 into blocking relation to the next successive tooth of the escape wheel 42, enabling the pallet to momentarily stop the movement of the escape wheel. As soon, however, as the pallet spring 48 is enabled to overcome the rotative force imparted to the pallet 44 by the escape wheel 42, this spring again rocks the pallet 44 out of the blocking position of Fig. 16 towards the free position of Fig. 17.

An important feature of the pallet 44, as il-

lustrated in Figs. 16 and 17, is the rounded corner 125 between the braking shoulder 124 and the notch 127 in advance of the tooth 122. It will be noted from Fig. 16 that the point on shoulder 124 engaged by the spoke of the escape wheel 42 is in an area which is cylindrical in form, but that a limited clockwise movement of the pallet 44 under the influence of spring 48 shifts the point of engagement to the rounded corner 125.

As the point of engagement moves over the rounded corner 125, the distance of the point of engagement from the center of staff 90 progressively decreases. This progressive decrease of the radius of the point of engagement has two important functions: first, it reduces the effect of the frictional resistance to clockwise rotation of pallet 44 to compensate for the progressive reduction in the force exerted by spring 48 and, second, it permits the escape wheel to begin its movement and accelerate before it is actually released by pallet 44, thus increasing the speed with which it strikes tooth 122.

It will be appreciated that the spring 48, balance wheel 46, pallet 44, hook 120 and staff 90 constitute an escapement system, which oscillates between the blocking and free positions shown in Figures 16 and 17, respectively. It will further be appreciated that the escape wheel 42 is enabled to advance one tooth during the course of one full cycle of movement of the just mentioned escapement system. The amplitude of the movement may be expected to vary somewhat in accordance with the loading of the main spring 38 and in accordance with the angular spacing between successive teeth of the escape wheel 42. The period or rate of the movement, however, is determined substantially entirely by the weight of the moving parts and by the tension of the spring 48, so that for any given tension of the spring 48, such rate or period is substantially independent of the loading of the main spring 38 and also is substantially independent of the angular spacing between the teeth of the escape wheel 42.

As afore-mentioned, the period or rate of the escapement can be varied over a substantial range by varying the tension of the spring 48, variations up to 30% having been found readily available in practice. It is preferred in practice, therefore, to employ the adjustment of the tension of the spring 48 as the means for calibrating the timer, an increase in tension serving to increase the escapement rate and a decrease in tension serving to decrease the escapement rate. This adjustment can, of course, be made by the simple expedient of turning the mounting screw 132 in one direction or the other.

As was previously mentioned, the escape rate appears to be substantially independent of the angular spacing between the successive teeth of the escape wheel 42. Consequently, by altering the number of teeth on the escape wheel, an exceedingly wide variation in the escape rate is readily available. More specifically, the escape wheel shown in Fig. 5 is provided with eight teeth, whereas the wheel of Fig. 18 is provided with four teeth. Accordingly, the wheel of Fig. 5 requires twice as long to make a complete revolution as does the wheel of Fig. 18, and the structure of Fig. 5 has one-half the escape rate of the structure of Fig. 18. It will be understood, of course, that by employing twice the number of teeth as are employed in the wheel of Fig. 5, the escapement rate is reduced by one-half, and that other proportionate increases and decreases of

the escape rate provided by the structure of Fig. 5 are obtainable by corresponding other proportionate decreases and increases in the number of teeth on the escapement wheel.

The actual escape rates employed and the gear ratio between the escape wheel and the arbor 32 determine, of course, the time interval afforded for each full 360° of movement of the arbor 32 and the dial 34, or for each fraction of such full movement. Various escape rates and gear ratios may be employed, as will be understood. By way of illustration but not of limitation, it is preferred to adjust the escapement so as to provide an escape rate of 216 escape teeth per minute, which corresponds, of course, with an eight-toothed wheel, to 27 escape wheel revolutions per minute and, with a four-toothed wheel, to 54 escape wheel revolutions per minute. It is further preferred to adjust the gear ratio between the escape wheel so that the eight-toothed wheel provides a sixty minute period for a full revolution of the dial. With this gear ratio, a four-toothed wheel, of course, provides a 30 minute timing interval and a sixteen-toothed wheel provides a two hour timing interval.

As previously mentioned, the movement plates 92 and 94 are maintained in fixed, spaced relation to each other by means of pillars 96, three of which are shown in the drawings and which are equiangularly spaced. A feature of the present construction resides in forming a positive but readily releasable connection between the pillars 96 and the plates 92 and 94. Referring particularly to Fig. 15, each movement plate is provided with a keyhole slot 99 individual to each pillar, and each pillar 96 is notched, as indicated at 97, to define flat-sided sections 95 which are narrow enough to pass through the neck of the corresponding keyhole slot. It will be understood that a pillar is assembled with respect to its plates 92 and 94 by rotating the pillar so as to bring the narrow portions 95 thereof into alignment with the necks of the keyhole slots, and that after the pillar is moved into the bases of the keyhole slots, the same is rotated through a slight angle so as to bring the narrow portions 95 out of alignment with the necks of the slots. The fit between the slotted pillars and the slots in the movement plates is preferably such as to frictionally prevent unintentional rotation of the pillars. It will further be appreciated that the notches 97 in the pillars 96 are spaced along the bodies thereof in accordance with the desired spacing between the movement plates 92 and 94, and that the length of each such notch is substantially equal to the thickness of the associated movement plate.

Referring particularly again to Figs. 2 and 4, the main spring 38 is of usual spiral form, one outwardly turned end 140 whereof is hooked through an opening provided therefor in the main spring housing 142, and the other inwardly turned end 144 whereof is hooked through a corresponding opening provided in the outer wall of a spring dog 146. It is preferred to anneal or otherwise treat the main spring prior to assembly so as to overcome any otherwise existing tendency of this spring to take a set after being placed in service.

The dog 146 is of cup-shaped form, the inner end whereof is open, and the base 148 whereof is provided with a non-circular opening, which non-rotatably receives the complementarily formed portions 149 of the arbor 32. The inner surface of the base 148 bears against shoulders, such as

150, formed on the arbor 32, and the dog 146 is maintained in place on the portions 149 by a nut 152, which is threaded on to the outer reduced end of the arbor 32. The main spring housing 142, in turn, is provided with a plurality of axially extending, circumferentially distributed teeth or projections 154, which project through corresponding openings provided in the front movement plate 92. The housing 142 may, therefore, 20 be secured to the movement plate 92 in any one of a plurality of rotative positions, each whereof corresponds to a different initial loading of the main spring 38.

The just described arrangement, wherein the main spring and its housing are mounted external to the movement plate and are readily connectible to and disconnectible therefrom, not only permits ready replacement of the main spring, but also serves a further important advantage of enabling the movement, comprising the arbor, the main gear, and the intermediate gears, to be freely run in before the escapement and the main spring are applied.

The setting dial 34 is herein illustrated as being formed of a plastic or other moldable composition, having a generally circular body portion provided with graduations 160, and having a blade-like or otherwise formed readily graspable central handle portion 162. The inner face of the dial 34 is provided with diametrically opposite pockets 164, which receive tongs 166 provided on a setting lever 168. The lever 168, in turn, is non-rotatably secured to the arbor 32, between the nut 152 and the dog 146. The dial 34 is also provided with a central recess 170, which receives the nut 152, and preferably, and as illustrated, a usual holding spring 172 surrounds the nut and frictionally engages the inner surface of the pocket 170. If desired, a set screw 174 or other means may be provided to more positively secure the dial 34 in assembled relation to the arbor 32.

The provision of a circular dial having the graduations distributed therearound is regarded as an important feature of the present construction. It will be appreciated from Fig. 1 that in the zero or re-set position of the timer, the zero point on the dial 34 registers with the reference mark 176 or other indication carried by the face plate 178. To set the timer, the dial 34 is rotated clockwise, as viewed in Fig. 1, from the just mentioned initial position, during which movement the graduations on the dial successively register with the reference mark 176 on the face plate. The interval for which the timer is set may thus be initially read at a fixed point on the unit, thus entirely overcoming the confusion which results from the use of dials wherein a movable pointer on the setting member is required to be moved into registry with fixed numerals distributed around the face plate.

60 From the description thus far given, it will be appreciated that the just mentioned clockwise setting movement of the dial 34 positively rotates the arbor 32 in a counterclockwise direction as viewed in Fig. 5, said rotation being transmitted to the arbor through the driving connection afforded by the setting lever 168. The just mentioned rotation of the arbor correspondingly drives the spring dog 146 in a counterclockwise direction, as viewed in Fig. 4, thereby winding up or loading this spring. The rotation of the arbor 32 applies a rotative force through the clutch plate 52, which tends to rotate the main gear 40 in a counterclockwise direction, as viewed in Fig. 75. This tendency is transmitted through the gear

train to the escape wheel 42 and tends to rotate the latter in a counterclockwise direction, which is the opposite to the direction of rotation normally imparted thereto by the main spring 38. The just mentioned reverse movement of the escape wheel 42 brings a tooth into engagement with the back of the tooth 122 on the pallet 44. The radius of the pallet in the region at the back of the tooth 122 is too great to allow a movement therepast, in a counterclockwise direction, of the escape wheel. The pallet 44 therefore operates to prevent reverse movement of the escape wheel and of the main gear 40. During a setting movement of the dial 34, therefore, the clutch plate 59 slips past the main gear 40. Upon release of the dial 34, however, the main spring 38 becomes effective to apply a torque to the arbor which rotates the latter in a clockwise direction, as viewed in Fig. 5, the rate of such clockwise or return movement being determined, of course, by the escapement, as aforescribed. The return movement is stopped at the zero position of the timer by the bell hammer mechanism now to be described, and at the conclusion of such movement also, the bell hammer mechanism operates to give one or more audible signals.

Referring particularly to Figs. 2 and 8 through 14, the hammer mechanism comprises generally a driving dog 180, a setting pawl coil 182, a plurality of hammers 184 and 185, two being shown by way of illustration, and a tripping lever 187. The dog 180 is illustrated as a cup-shaped stamping having a non-circular opening in its base which co-operates with flats such as 181 on the arbor 32 to provide a driving connection for the dog 180. The inner face of the dog 180 engages the trip lever 187, and movement of the dog 180 along the arbor 32 in the other direction is limited by the overlying portion 189 of the hereinbefore mentioned bracket 204. The pawl 182 is of generally bell crank shape having legs 186 and 188. A pair of ears 190 extend laterally from the leg 186, and are provided with bearing openings through which the reduced end portion 192 of the arbor 32 is freely passed. The pawl 182 is normally maintained in seating relation to the dog 180 by means of a compression spring 196 which surrounds the reduced portion 192 of the arbor, and which spring normally causes the dog 180 to engage the lever 187. One end of spring 196 bears against the leg 188 and the other end thereof bears against the leg 186 of the pawl. The latter end of the spring is straightened, and is received in a notch 198 cut in the reduced portion 192 of the arbor. With this relation, it will be appreciated that any movement of the pawl 182 to the right, as viewed in Fig. 2, compresses the spring 196 somewhat, rendering it effective, upon release of the pawl, to restore the latter to the normal position shown in Fig. 2.

A driving lug 200, having a sloping back, is pressed outwardly from the driving dog 180, and upon rotation of the dog 180 in a counterclockwise direction, from the off position shown in Fig. 9, toward the on position shown in Fig. 8, the abrupt face of the lug 200 engages behind the leg 186 of the pawl 182, and applies a rotative force to the latter. The just mentioned rotation of the pawl 182 brings the hammers 184 and 185 from the tripped positions of Fig. 9 to the cocked positions of Fig. 8, as hereinbefore described. Shortly after the pawl reaches a position in which the hammers assume the cocked positions, the leg 183 of the pawl encounters a gradually rising cam surface 292 which is struck from the body of a

bracket 204 which is rigidly but adjustably secured to the rear movement plate 94. The continued movement of the pawl past the cam surface 292 enables the latter to cam the pawl 182 from the position shown in Fig. 2 to a position far enough to the right thereof to clear the lug 200. When the lug 200 clears the pawl 182, the driving force of the dog 180 on the latter is relieved, enabling a continued setting movement of the dial and of the arbor 32 without further altering the position of the pawl 182. On the other hand, during the return or timing movement of the arbor 32, the dog 180 moves in a clockwise direction, as viewed in Figs. 8 and 9. Due to the fact that the pawl 182 frictionally engages the surface of the dog 180, and also has a frictional engagement with arbor 32, the return movement of the arbor 32 may serve to return the pawl 182 from the setting position shown in Fig. 8 to the setting position shown in Fig. 9. If not, the gradual return movement of the dog 180 ultimately brings the grounded back of the lug 200 into engagement with the front face of the pawl leg 186, enabling the dog 180 to rotate the pawl 182 to the normal position of Fig. 9. A limit to the return movement of the pawl 182 is afforded by a lug 206 which is struck outwardly from the previously mentioned bracket 204. As soon as the pawl 182 engages the lug 206, the further movement thereof is interrupted, and the continued movement of the dog 180 enables the sloping back of the lug 200 to again lift the pawl 182 off its seat, enabling the lug 200 to pass behind the pawl to the normal position shown in Fig. 9.

Except as hereinbefore noted, the hammers 184 and 185 are duplicates. The hammer 184 compresses a relatively heavy head 210, which is secured at the outer end of a length of relatively heavy spring wire 212, the other end whereof is rigidly secured to a post 213 which is secured to and projects from the previously mentioned bracket 204. In the released position of the hammer shown in Fig. 9, the wire 212 bears, at an intermediate point, against one of the previously mentioned pillars 96, which acts to limit the radial outward movement of the hammer head 210. The head 210 is made up of two complementary portions 210a and 210b which are permanently secured to each other, as by riveting over the ends of the tongues 210c, formed on the member 210a, and which project through corresponding openings provided therefor in the body of the member 210b. The free end of the wire 212 is rigidly clamped between the portions 210a and 210b.

The head member 210b is provided with an extended arm 214, having a finger 216 which lies in the path of movement of leg 188 of the pawl 182 and also having a hook 218. In the cocked position of the hammer, the hook engages the latch 220 which may be and preferably is formed as a flange projecting from the bracket 204. As most clearly appears in Fig. 10, the flange 220 is provided with a slot 222 individual to each hammer. In the cocked position of each hammer, the hook 218 thereof engages over the lower end of each slot 222.

It will be appreciated that the tripping of the hammers 184 and 185 from the cocked positions of Fig. 8 enables these hammers to give the signals for which the device is designed and this tripping action is accomplished by means of the previously mentioned tripping lever 187, which is loosely journaled on the arbor 32 for swinging

movement from the off position shown in Fig. 9 to the on position shown in Fig. 8.

The previously mentioned driving dog 180 is provided with an inwardly struck lug 230, and the just mentioned tripping lever 187 is provided with an outwardly struck lug 232 which lies in the path of movement of the lug 230. The normal position of the parts is that shown in Fig. 12, in which the lug 230 lies immediately in front of, but in engagement with, the lug 232 and in which position the nose 234 of the tripping lever 187 engages an abutment 236 formed on the previously mentioned bracket flange 220. The tripping lever 187 thus co-operates with the dog 180 to form a limit stop to the return or timing movement of the timing device, and it will be understood that the dog 180 drives the lever 187 into engagement with the abutment 236 when the zero point on the dial 34 registers with previously mentioned mark 176 on the face plate 178 (Fig. 1). A setting movement of the timer, as previously described, causes the arbor 32 to drive the dog 180 in a counterclockwise direction, as viewed in Figs. 8 and 9. This movement causes the lug 230 to move away from the lug 232. The friction between the interengaging marginal edge portions of the dog 180 and the lever 187 enables the dog 180 to frictionally move the lever 187 from the off position of Fig. 9 to the on position of Fig. 8. In the latter position, the nose 234 thereof engages an abutment 236 formed on the previously mentioned bracket 234. After, as the just mentioned limit to the movement of the tripping lever 187 is reached, slippage occurs between the lever 187 and the dog 180, enabling the latter to continue in the counterclockwise direction without further altering the position of the lever 187.

If the setting movement of the dial is continued throughout the full 360 degrees of movement thereof, the concluding part of such movement brings the lug 230 into engagement with the back of the lug 232. Consequently, the tripping lever 187 co-operates with the dog 180 not only for the purpose of forming a limit stop to the return movement of the timer, but also for the purpose of forming a limit stop to the setting movement thereof.

Assuming that the setting movement of the dog 180, as influenced by the dial 34, is interrupted either when the just mentioned limit is reached or is interrupted at an intermediate position, the release of the dial 34 enables the main spring 38 to initiate a return or timing movement of the dog 180. During the course of the just mentioned return movement, the lug 230 again engages the face of the lug 232 and continued return movement of the dog 180 cams the trip lever 187 from the on position of Fig. 8 towards the off position of Fig. 9. During this movement of the lever 187, the flange 242 formed thereon engages under the noses 244 of the hammer arms 214. This action enables the tripping lever 187 to cam the noses 244 radially outwardly, as viewed in Fig. 8, and ultimately releases these arms from the latch 220. Upon being released, the energy stored in the springs 212 associated with the individual hammers whips the heads of the hammers radially outwardly, as viewed in Figs. 8 and 9. During the course of this whipping movement, the springs engage the supporting post 96, as described previously, so that the final whipping movement occurs as a result of fluxure of that part of each spring between the pillar 96 and the associated head. The weight of the heads 210 carries them

to the position shown in Fig. 9, enabling them to strike the bell 246 associated with the timer.

It is sometimes desired to produce two bell notes or two successive operations of the hammers 214 at spaced intervals. This result may be accomplished, as shown in Fig. 10, by making the edge 243 of flange 242 of stepped form, or alternatively, if the edge 243 is a straight edge, by providing slightly different tapers on the undersides of the noses 244 of the hammer arms, which portions are engaged by the flange 242 of the tripping lever.

It will be noted from Figs. 2 and 10, that the movement 36 and the principal parts of the hammer mechanism are housed within a cup-shaped enclosure 250. The base of the enclosure 250 is provided with three openings, through which the extreme ends of the pillars 96 are passed, and in order to secure the enclosure 250 against axial movement off of the pins, a conventional clip spring 252 is preferably employed, the body whereof hooks beneath grooves formed in the pin extremities, as will be understood. The side of the enclosure 250 is provided with an opening 254, through which the heads of the hammers 184 and 185 may project upon being tripped by the tripping lever 187, and in the present instance, the bell 246, which is also of generally cup shape, is secured directly to the back of the enclosure 250 by means of a countersunk screw 256.

A feature of the present arrangement resides in an improved method for mounting and adjusting the hammers, it being appreciated that in order to ensure a clear, unblurred note from each hammer, the normal spacing between each hammer-head and the inner surface of the bell should be held between rather close limits. In view of the fact that each hammer is carried by a section of spring wire, and further in view of the fact that the characteristics of this wire vary somewhat, the present invention provides for the use of a fixture having pillars corresponding to the pillars 214 and 96, against which each spring 212 bears, as viewed in Figs. 8 and 9, together with means for supporting the head elements 210a and 210b in proper position. Thus, the free end of the spring 212 may be allowed to take up a free radial position between the head elements 210a and 210b, after which the elements 210a and 210b may be rigidly secured together with the spring 212 clamped therebetween.

It will be recalled from the previous description that the abutment 240 on the hammer bracket 204 co-operates with the tripping lever 187 to form a limit to the setting movement of the timer, and that the abutment 236 carried by the bracket 204 co-operates with the lever 187 to form a limit to the return or timing movement of the timer. Accordingly, in order to allow for initial adjustment of the timer, so as to insure that the zero point on the dial 34 will arcuately register with the mark 176 on the face plate 178 in the reset position of the timer, the bracket 204 is rotatably adjustable relative to the movement plate 92. For this purpose, the bracket 204 is secured to the movement plate 92 by means of three circumferentially distributed screws 260, each whereof may be threaded into a tapped opening in the movement plate 92, and each whereof passes through an elongated slot formed in the bracket 204. As illustrated, fine adjustments of the bracket 204 are facilitated by providing the latter with a series of gear-like teeth 262, which are disposed for meshing engagement with corresponding teeth on a tool (not shown) which may be introduced into a drilled opening 264 in the mounting plate 92 and

rotated so as to correspondingly rotate the bracket 204.

It will be noted from the previous description that the entire timer assembly is directly supported by the movement plates 92 and 94. In order to secure the timer to the face plate 178, it is preferred to provide the latter with a plurality of inwardly struck lugs 261, which pass through corresponding slots formed in the movement plate 92 and which lugs may be slightly twisted by a pair of pliers or similar tool so as to lock the parts in assembled relation to each other. The twisting of the lugs draws the inner marginal edge of the enclosure 259 into engagement with the inner face of the face plate 178. The face plate 178 may, of course, be secured to any suitable casing or box in any desired manner. The just mentioned twistable lugs are found in practice to admit of frequent removals of the movement from the face plate without impairing the efficiency of the connection, or without causing the lugs to break off.

The present escape mechanism is found in practice to operate relatively quietly. In certain instances, however, it is found preferable to utilize the somewhat resilient escape wheel construction, shown in Figs. 20 and 21. In these figures the escape wheel 273 is formed of a single sheet of metal, such, for example, as spring bronze. The center body portion is planar and is provided with an opening 272 to receive the supporting arbor or staff. The successive teeth of the escape wheel 273 are constituted by flat ends 274 and spokes 276. It will be noticed that the ends 274 are substantially co-planar with the center body portion of the wheel, but that the spokes 276 are twisted relative to the ends and the body through approximately 90 degrees, so that such spokes relatively readily flex slightly when they engage the associated pallet, such as 44. This flexing softens each impact between the escape wheel and the pallet and consequently makes the operation of the escapement wheel exceedingly quiet.

Considering now the operation of the timer as a whole, it will be appreciated that the parts are shown in Figures 1 and 9 in the normal, or off, position thereof, in which the zero point on the dial 34 registers with the mark 176 on the face plate 178 and in which the hammers 184 and 185 occupy their released positions. In these latter positions the springs associated therewith bear against the associated movement pillar 96, and are thereby maintained out of contact with the bell 246. Under these conditions, also, the main spring is subjected to a normal loading determined, as previously described, by rotating the spring housing 142 relative to the arbor as an incident to the assembling of the main spring with the movement 36. The main spring thus urges the arbor 32 in a clockwise direction, as viewed in Figure 9, tending to move the dial in a counter-clockwise direction (Figure 1) past the zero point. Such movement is, however, prevented by the engagement of the nose 234 of the tripping lever 187 with the abutment 236 on the adjusting bracket 204. Until set by the dial 34, therefore, the timer remains at rest at the just mentioned zero position.

Assuming it is desired to effect an operation of the timer, the dial 34 may be rotated in a clockwise direction, as viewed in Figure 1, throughout all or part of the permitted 360° of movement thereof. The arbor 32 moves directly with the dial during this setting movement. The initial arbor movement drives the movement 36 in an

opposite direction until such a time as a tooth of the escape wheel 42 binds against the back of the pallet tooth 122, thereby blocking further such reverse movement. Following this blocking action, the continued movement of the arbor 32 causes slippage of the clutch plate 58 past the main timer gear 40. The setting rotation of the arbor 32 also winds up the main spring 38, as previously described.

The setting rotation of the arbor 32 causes a corresponding rotation of the dog 180 associated with the hammer mechanism. The initial such rotation of the dog 180 rocks the pawl 182 in a counterclockwise direction, as viewed in Figure 9, enabling the leg 188 thereof, through its engagement with the fingers 216 of the hammer arms 214, to move the hammers from the off, or tripped, position of Figure 9 to the cocked positions of Figure 8, at the conclusion of which movements the hammer arms snap behind latching bracket 220. Shortly after the just mentioned latching of the hammers is effected, the arm 186 of the pawl 182 rides up on the lug 202 and is thereby cammed to the right, as viewed in Figure 2, far enough to clear the driving lug 200 on the dog 180. It will be appreciated that the setting movement may be stopped at any time after the cocking of the hammers is effected, which cocking may be arranged to take place in the course of a relatively few degrees of rotation of the dial 34.

Due to the frictional connection between the dog 180 and the tripping lever 187, the initial rotation of the dog 180 moves the tripping lever from the off position of Figure 9 to the on position of Figure 8, in readiness to provide a limit stop to the setting movement of the dial 34. This movement of the tripping lever 187 also carries the flange 242 thereof out of co-operative relation to the noses 220 of the hammer arms so that the tripping lever 187 does not interfere with the cocking of these hammers.

If the setting movement is continued throughout the full 360° of permitted movement thereof, the final such movement thereof brings the lug 230 on the dog 180 into engagement with the back of the lug 232 on the tripping lever 187, thereby tending to rotate the latter in a counterclockwise direction beyond the position shown in Figure 8. Any such further movement is, however, prevented by the engagement of the nose 238 of the tripping lever with the abutment 240 on the adjustable bracket 204. The lever 187, therefore, prevents movement of the dial 34 beyond the full 360° of movement.

Assuming the dial 34 is released at any point between the point at which the hammers are cocked and the just mentioned limit position, the main spring 38 is immediately rendered effective to drive the arbor 32 in a clockwise direction (Figures 5, 8 and 9) at a rate determined by the escapement which controls the return movement of the arbor 32 through the clutch connection between the clutch plate 58 and the main gear 40. During the course of such return movement of the arbor 32, the dog 180 may be expected to frictionally drive the pawl 182 back to the position of Figure 9. If the frictional force is not sufficient to do this, the continued movement of the dog 180 brings the lug 200 into engagement with the back of the pawl arm 186, enabling the latter to positively return the pawl. When the pawl reaches the normal position shown in Figure 9, the arm 186 thereof engages the fixed lug 206, enabling the lug 200 to cam the pawl 182

to the right, as viewed in Figure 2, far enough to permit the lug 200 to pass behind the pawl and resume the position shown in Figure 9. As the dog 180 approaches the zero, or starting, position, the lug 230 on the dog 180 comes into engagement with the lug 232 on the tripping lever 187. Continued return movement of the dog 180 swings the tripping lever 187 from the on position of Figure 8 toward the off position of Figure 9. In the course of this movement, the flange 242 on the tripping lever 187 successively engages the noses 220 on the hammer arms 214 and cams these arms out of engaging relation to the latch 220. As each hammer arm is released from the latch, the energy stored in the spring 212 associated therewith whips the head of the hammer into engagement with the bell 246, as described above. It will be understood that the interval between each bell note is determined by the configuration or proportioning of the noses 244 of the arms 214, it being preferred, of course, that the final bell note be timed to occur substantially simultaneously with the arrival of the dial at the zero position. When the dial arrives at the zero position, also, the nose 234 of the tripping lever 187 engages the abutment 236 on the bracket 204, thereby stopping the return, or timing, movement.

As described above, the escape rate of the present mechanism can be varied over a substantial range by adjusting the tension of the spring 48 and by changing the number of teeth on the escape wheel 42. For each escape rate, also, the time required for a full 360° of travel of the dial depends upon the gear ratio employed. Certain changes in the gear ratio can best be made by the addition to or elimination from the gear set of one or more gears. In certain instances it is, therefore, desirable to arrange the escape mechanism to accommodate rotation of the escape wheel 42 in either direction. Such an arrangement is shown in Figs. 24, 25 and 26, in which the pallet 44' is provided with a single radially projecting finger 122', the respectively opposite radial faces whereof correspond to the previously described shoulder 122. In addition, the pallet 44' is provided with two shoulders 124' and 124'', which individually correspond to the shoulder 124 and which are symmetrically arranged at either side of the finger 122'. The rotative position of the spring bracket 120 with respect to the pallet 44' and the mounting for the fixed end of the spring 148 are such that the spring 48 always tends to rock the finger 122' to a position in which it lies between and on a line with the axis of the pallet shaft 90 and the axis of the escape wheel 42.

As will be appreciated, Figs. 24 and 26 correspond, respectively, to Figs. 16 and 18, and the operation of the escapement, considering clockwise rotation of the escape wheel 42, is the same as previously described with reference to Figs. 16 and 18. If, however, the gearing is changed so as to produce counterclockwise rotation of the escape wheel 42, the parts cooperate as shown in Fig. 25. That is to say, the tooth of the escape wheel bears against the righthand radial face of the finger 122' and urges the pallet 44' in a clockwise direction sufficiently far to bring the shoulder 124'' into blocking relation to the next succeeding escape wheel tooth. The spring 48 opposes the just-mentioned rotation of the pallet 44' and swings the same in a counterclockwise direction, thereby releasing such next succeeding escape wheel tooth from the shoulder 124'' and

allowing such tooth to advance and strike the finger 122' as just described. In other respects, the operation depicted in Fig. 25 is the same as previously described.

In Figures 27 and 28 is illustrated a further modification of the escapement, in which the escapement element, or pallet, is formed integrally with the balance staff and a slightly modified form of resilient escapement wheel is provided. As shown best in Figures 27 and 28, the balance staff 90' is illustrated on a larger scale than in Figures 24 to 26. The balance staff 90', however, except for the details of the escapement element itself, hereinafter described, is similar in arrangement and construction to the balance staff 90, previously described and illustrated. In this form of the invention, the escapement element or pallet 280 is similar in form to the element 44', illustrated in Figures 24 and 26, being provided with a pair of shoulders 281 forming braking surfaces, a pair of escape notches 282, and an intermediate radial projection 283 which extends radially to a substantially greater degree than the shoulders 281 and which receives the impulse from the escapement wheel. The escapement element 280, including the escape notches and the radial projection 283, is formed integral with and from the balance staff 90' by a stamping operation, in the manner illustrated in Figure 29. As shown in Figure 29, the balance staff 90' is placed between a pair of die elements 290 and 291 which, when forced together, form the notches 282 in the balance staff and extrude the metal which formerly occupied the notched spaces to form the radial projection or impulse member 283.

It will be observed that in the escapement element of Figures 27 and 28, as well as the escapement element of Figure 24, the corner between the braking surface and the notch is rounded in the manner illustrated and described in connection with the pallet 44, illustrated in Figures 16 and 17, except that the notches and braking surfaces are duplicated in the reversible form of pallet.

The form of escapement element or pallet illustrated in Figures 27 and 28 may be used equally well with an escapement wheel of the form illustrated in Figures 24 to 26 or of the form illustrated in Figures 20 and 21. However, there is illustrated in Figure 27 a further modified form of escapement wheel 292 provided with a plurality of resilient teeth 293. The escapement wheel 291 is formed of sheet metal and has a flat central portion 294 secured in any suitable manner to a hub 295, which is provided with pinion teeth 296 adapted to mesh with the teeth of gear 76 in the manner illustrated in Figure 7. The teeth 293 are formed integrally from the same sheet of metal as the central portion 294, and are initially of the width indicated in dotted lines at 291. However, after the wheel is blanked out of the sheet metal, the teeth are twisted through an angle of 90° at the point 298 adjacent the bases so that the plane of the teeth extends parallel to or contains the axis of the wheel. This produces a relatively thin, flat-bladed resilient tooth for cooperation with the escapement element 280 in the manner described in connection with the resilient escapement wheel illustrated in Figures 20 and 21.

It will be understood that the form of escapement wheel illustrated in Figure 27 may be substituted for the escapement wheel 42 in Figures

16 and 17 or for the escapement wheel 42 in Figures 24 to 26, if desired.

While several specific embodiments of the invention have been described in detail, it will be appreciated that various modifications in the form, number and arrangement of parts may be made without departing from the spirit and scope of the invention.

What is claimed is:

1. An escapement mechanism comprising an oscillating balance staff, means directly on and movable with said staff forming an escapement space permitting escapement of teeth successively, said means also having a braking surface associated therewith, and an escapement wheel having peripherally arranged resilient teeth cooperating with said means mounted on the staff for escapement through said space, and cooperable with said braking surface prior to passage through said space.

2. An escapement mechanism comprising an oscillating staff, an escapement member mounted on and movable with the staff, said member having an extension therefrom and a braking surface thereon with space therebetween, and an escapement wheel having peripherally arranged resilient teeth cooperating resiliently with the braking surface of the escapement member and passing through said space into resilient cooperation with said extension for driving the latter.

3. An escapement wheel comprising peripherally arranged teeth, each of which consists of a plane of springy material arranged as a cantilever, said plane having an outer edge of substantial length which is substantially parallel to the axis of the wheel.

4. An escapement mechanism comprising an oscillating balance staff, means on said staff forming an escapement space permitting escapement of teeth successively, said escapement means also having an extension and a braking surface associated therewith, and an escapement wheel having peripherally arranged resilient teeth cooperating resiliently with the braking surface of the resilient member and passing through said space and cooperating with said extension for driving the latter, the plane of resilient movement of said teeth being parallel to the plane of movement of said extension.

5. An escapement mechanism comprising a rotatable escapement wheel having a plurality of peripherally arranged teeth, an oscillating balance staff, and escapement means directly on and movable with said staff for permitting escapement of said teeth progressively, said means having a braking surface for successively engaging said teeth and a substantially radially projecting impulse surface adapted to be struck by each tooth as it is released from said braking surface, said braking surface and impulse surface being separated by a notch of sufficient size to permit passage of one tooth of said wheel at a time, said braking surface being a curved surface whose radius from the axis of said means progressively decreases as the surface approaches said notch beginning with a curve approximately concentric to the axis of oscillation of said means and terminating at said notch in a curve whose tangent is approximately perpendicular to the plane of said impulse surface and said impulse surface projecting from said axis of oscillation a substantially greater distance than any part of said braking surface.

6. An escapement mechanism comprising a rotatable escapement wheel having a plurality of peripherally arranged teeth, an oscillating balance staff, and escapement means directly on and movable with said staff for permitting escapement of said teeth progressively, said means having a braking surface for successively engaging said teeth and a substantially radially projecting impulse surface adapted to be struck by each

tooth as it is released from said braking surface, said braking surface and impulse surface being separated by a notch of sufficient size to permit passage of one tooth of said wheel at a time, said braking surface being a curved surface whose radius from the axis of said means progressively decreases as the surface approaches said notch beginning with a curve approximately concentric to the axis of oscillation of said means and terminating at said notch in a curve whose tangent is approximately perpendicular to the plane of said impulse surface.

7. An escapement mechanism comprising a rotatable escapement wheel having a plurality of peripherally arranged teeth, an oscillating balance staff, and escapement means directly on and movable with said staff for permitting escapement of said teeth progressively, said means having a braking surface for successively engaging said teeth and a substantially radially projecting impulse surface adapted to be struck by each tooth as it is released from said braking surface, said braking surface and impulse surface being separated by a notch of sufficient size to permit passage of one tooth of said wheel at a time, said braking surface being a curved surface whose radius from the axis of said means progressively decreases as the surface approaches said notch and said impulse surface projecting from said axis of oscillation a substantially greater distance than any part of said braking surface.

8. An escapement mechanism comprising a rotatable escapement wheel having a plurality of peripherally arranged teeth, an oscillating balance staff, and escapement means directly on and movable with said staff for permitting escapement of said teeth progressively, said means having a braking surface for successively engaging said teeth and a substantially radially projecting impulse surface adapted to be struck by each tooth as it is released from said braking surface, said braking surface and impulse surface being separated by a notch of sufficient size to permit passage of one tooth of said wheel at a time, said braking surface being a curved surface whose radius from the axis of said means progressively decreases as the surface approaches said notch beginning with a curve approximately concentric to the axis of oscillation of said means and terminating at said notch in a curve whose tangent is approximately perpendicular to the plane of said impulse surface and said impulse surface projecting from said axis of oscillation a substantially greater distance than any part of said braking surface.

9. A reversible escapement mechanism comprising a rotatable escapement wheel having a plurality of peripherally arranged radially projecting teeth, an oscillating balance staff having a radial projection defining a pair of oppositely directed substantially radially extending impulse surfaces, one impulse surface being adapted to be engaged successively by said teeth when said wheel is rotating in one direction and the other adapted to be engaged successively by said teeth when said wheel is rotating in the other direction, said element having a notch formed therein at each side of said projection, one notch being adapted to permit passage of one of said teeth at a time into contact with said projection when the wheel rotates in one direction and the other notch being adapted to permit such passage of one of said teeth at a time into contact with said projection when the wheel rotates in the opposite

direction, and said element having at the opposite sides of each notch from said projection a braking surface adapted when the element is in one rotative position to engage one of said teeth and interrupt the movement of said tooth toward the projection and adapted to permit movement of said tooth through the notch and into engagement with said projection when the element is in another rotative position, one of said braking surfaces being operative when the wheel is rotating in one direction and the other braking surface being operative when the wheel is rotating in the opposite direction, and a spring eccentrically connected to said balance staff and having a dead center position when said projection extends toward the axis of said wheel.

10. A reversible escapement mechanism comprising a rotatable escapement wheel having a plurality of peripherally arranged radially projecting teeth, an oscillating balance staff having an escapement element fixed to said balance staff and having an integral radial projection defining a pair of oppositely directed substantially radially extending impulse surfaces, one impulse surface being adapted to be engaged successively by said teeth when said wheel is rotating in one direction and the other adapted to be engaged successively by said teeth when said wheel is rotating in the other direction, said balance staff having a notch formed directly therein at each side of said projection, one notch being adapted to permit passage of one of said teeth at a time into contact with said projection when the wheel rotates in one direction and the other notch being adapted to permit such passage of one of said teeth at a time into contact with said projection when the wheel rotates in the opposite direction, and said balance staff having at the opposite sides of each notch from said projection a braking surface adapted when the balance staff is in one rotative position to engage one of said teeth and interrupt the movement of said tooth toward the projection and adapted to permit movement of said tooth through the notch and into engagement with said projection when the balance staff is in another rotative position, one of said braking surfaces being operative when the wheel is rotating in one direction and the other braking surface being operative when the wheel is rotating in the opposite direction, and a spring eccentrically connected to said balance staff and having a dead center position when said projection extends toward the axis of said wheel.

11. A unitary balance staff and escapement element comprising a generally cylindrical shaft having a radial projection formed integrally therewith, said shaft having notches at each side of the projection adapted to act as escapement spaces.

12. An escapement mechanism comprising an oscillating balance staff, a shaft extending parallel to said staff, an escapement wheel on said shaft, said wheel having a central sheet metal web portion and resilient peripheral teeth projecting substantially radially from said web portion and integral with said web portion, means directly on and movable with said staff defining a peripheral braking surface adapted in one rotative position of said staff to engage the extremity of one of said teeth and block movement of said wheel, said means defining the braking surface being adapted on rotation of said staff in one direction from said position to release said tooth and permit rotation of said wheel, a spring act-

ing to rotate said staff in said one direction when said braking surface is in engagement with a tooth of said wheel, and means directly on and movable with said staff forming a substantially radially projecting impulse surface in a position to be engaged by the extremity of each tooth of said wheel when the tooth is released from said braking surface and to be moved by the tooth in a direction to rotate said staff in the opposite direction into the position in which said braking surface engages the next succeeding tooth of said wheel.

13. An escapement mechanism comprising an oscillating balance staff, a shaft extending parallel to said staff, an escapement wheel on said shaft, said wheel having a central sheet metal web portion and resilient peripheral teeth projecting substantially radially from said web portion and integral with said web portion, means directly on and movable with said staff defining a peripheral braking surface adapted in one rotative position of said staff to engage the extremity of one of said teeth and block movement of said wheel, said means defining the braking surface being adapted on rotation of said staff in one direction from said position to release said tooth and permit rotation of said wheel, said peripheral braking surface terminating adjacent the releasing extremity thereof in a peripheral braking surface of progressively decreasing radius from the axis of said staff to effect a gradual release of said tooth as said staff rotates in said one direction, a spring acting to rotate said staff in said one direction when said braking surface is in engagement with a tooth of said wheel, and means directly on and movable with said staff forming a substantially radially projecting impulse surface in a position to be engaged by the extremity of each tooth of said wheel when the tooth is released from said braking surface and to be moved by the tooth in a direction to rotate said staff in the opposite direction into the position in which said braking surface engages the next succeeding tooth of said wheel.

14. An escapement mechanism comprising a rotatable escapement wheel having a plurality of peripherally arranged teeth, an oscillating balance staff, and escapement means directly on and movable with said staff for permitting escapement of said teeth progressively, said means having a peripheral braking surface for successively engaging said teeth and a substantially radially projecting impulse surface adapted to be struck by each tooth as it is released from said braking surface, said braking surface and impulse surface being separated by a notch of sufficient size to permit passage of one tooth of said wheel at a time, said braking surface being a curved surface having a portion adjacent said notch whose radius from the axis of said means progressively decreases as the surface approaches said notch beginning with a curve approximately concentric to the axis of oscillation of said means and terminating at said notch in a curve whose tangent is approximately perpendicular to the plane of said impulse surface.

15. An escapement mechanism comprising an oscillating balance staff, a shaft extending parallel to said staff, an escapement wheel on said shaft and having peripheral teeth extending substantially radially therefrom, means directly on and movable with said staff defining a peripheral braking surface adapted in one rotative position of said staff to engage the extremity of one of

said teeth and block movement of said wheel, said means defining the braking surface being adapted on rotation of said staff in one direction from said position to release said tooth and permit rotation of said wheel, said peripheral braking surface terminating adjacent the releasing extremity thereof in a peripheral braking surface of progressively decreasing radius from the axis of said staff to permit a gradual release of said tooth as said staff rotates in said one direction, a spring acting to rotate said staff in said one direction when said braking surface is in engagement with a tooth of said wheel, and means directly on and movable with said staff forming a substantially radially projecting impulse surface extending radially to a greater extent than the maximum radius of said braking surface and adapted to be engaged by each tooth of said wheel when the tooth is released from said braking surface and to be moved by the tooth in a direction to rotate said staff in the opposite direction to shift said staff into the position in which said braking surface engages the next succeeding tooth of said wheel.

CHARLES E. GODLEY.
